United States Patent Office

Des. 224,293

Patented July 18, 1972

224,293

COMFORT STATION SHELTER OR SIMILAR ARTICLE

Robert S. Wormser, Hillsdale, Mich., assignor to Game
Time Inc., Litchfield, Mich.

Filed Mar. 18, 1971, Ser. No. 125,908

Term of patent 14 years

Int. Cl. D25—03

U.S. Cl. D13—1

FIG. 1

FIG. 2

FIG. 4

FIG. 3

FIG. 1 is a left side elevational view of a comfort station shelter or similar article showing my design, the right side appearing as the mirror image thereof,

FIG. 2 is a front elevational view of my design,

FIG. 3 is a rear elevational view, and

FIG. 4 is a top plan view of my design.

I claim:

The ornamental design for a comfort station shelter or similar article, substantially as shown and described.
